[57] CLAIM

The ornamental design for package for wipes, as shown and described.

DESCRIPTION

FIG. 1 is a perspective view of a package for wipes showing my new design;

FIG. 2 is a front elevation thereof;

FIG. 3 is a rear elevation thereof;

FIG. 4 is a right side elevation thereof;

FIG. 5 is a left side elevation thereof;

FIG. 6 is a top plan view thereof;

FIG. 7 is a bottom plan view thereof;

FIG. 8 is a perspective view thereof; showing undisclosed sides in FIG. 1;

FIG. 9 is a sectional view thereof; taken along line 9—9 of FIG. 6;

FIG. 10 is a sectional view thereof; taken along line 10—10 of FIG. 6;

FIG. 11 is a sectional view thereof; taken along line 11—11 of FIG. 6; and

FIG. 12 is a perspective view thereof; in open position. The broken lines showing of wipes is for illustrative purpose only and forms no part of the claim.
